FOOT-BALANCING MEANS

Charles P. Leydecker, St. Louis, Mo.

Application October 8, 1936, Serial No. 104,646

2 Claims. (Cl. 36—71)

The present invention relates generally to shoes, and more particularly to a method for effecting foot balance within a shoe, and means for achieving such balance.

The present invention is predicated upon the theory that there is only one longitudinal bone arch in the foot construction, the columns or supports of which comprise the os calcis and the forward portion of the first metatarsal. Many authorities aver that there are three or four arches in the longitudinal dimension of the foot; but a study of the bones in the feet shows that the many bones which comprise a foot make up one complete arch, some parts of which are concave and some parts of which are convex, but all of which contribute to the one single arch.

Modern shoe construction has resulted in the dropping of certain bones of the foot, notably the cuboid and the fifth metatarsal, so that the rear portion of the fifth metatarsal contacts the shoe in walking which, in effect, provides two arches, namely, one between the os calcis and the rear portion of the fifth metatarsal, and the other between the rear portion of the fifth metatarsal and the forward portion of the first metatarsal or the great toe. This, however, is not a natural position. This lowering of the enumerated bones of the feet has been caused by constructing shoes with heels, which raises the position of the os calcis relative to the forward portion of the first metatarsal. Many devices have been devised in an effort to compensate for the position of the bones in the foot in this man-made position relative to the ground; and none of them has been singularly successful. Many have concentrated on supporting the inner side of the foot at the center of the arch by means which are generally designated arch supports. However, few have seriously considered the outer side of the longitudinal arch which, in the final analysis, is the primary weight carrier of the foot. Experiment has shown that the weight of the body in walking is carried from the os calcis, or heel bone, as one main support along a substantially curved line through the cuboid and the fifth metatarsal to the forward portion of the first metatarsal as the second main support. In other words, in walking, the weight of the body is distributed along the outer edge of the foot in an arc of a circle from the heel bone to the forward portion of the first metatarsal. The foot has a tendency to roll, which is a balanced movement when the heel is not maintained raised relative to the metatarsals.

Before proceeding, it should be observed here

that the lower portion or supporting surface of the os calcis is not flat, but is higher on the inner side and has a tuberosity on the outer side which allows the weight to be shifted forward without wobbling of the foot until the weight reaches the cuboid and the base of the fifth metatarsal. By this construction, the heel bone shifts the weight forwardly gradually rather than abruptly. As the weight is shifted forwardly, the base of the fifth metatarsal, which is, in effect, a marked protuberance, assists in the forward shifting thereof by contact with the walking surface. However, when the heel bone is elevated, the base of the fifth metatarsal is likewise relatively elevated and, to contact the walking surface, must drop a greater degree, which results in straining the main longitudinal arch, inasmuch as the bone structure must give to allow this unnatural ultimate position of the base of the fifth metatarsal. This dropping downwardly of the rear portion of the fifth metatarsal accentuates the rolling weight distribution throughout the foot and results in the turning over of the shoe which is one of the greatest wear points in modern shoe construction; inasmuch as the majority of shoes, after being worn a short while, show this overturning outwardly of the upper over the edge of the sole. The present invention contemplates correcting this distorted action of the bone structure by providing a natural support for the base or rear portion of the fifth metatarsal which will alleviate strain in the foot and save this undue overturning of the shoes outwardly.

The above noted undue lowering of the outside bone structure of the foot, resultant of raising the heel relative to the forward portion of the first metatarsal, strains the whole foot structure and causes tiring of an individual prematurely. Only when the foot is properly balanced is the circulation of the blood normal and can the blood enter and leave the pedal extremity without straining the heart. There are nerves passing through the feet which transmit the proper amount of nerve impulses when the circulation is normal, and quite obviously impoverished circulation will lead to subnormal nerve impulses and resultant impaired activity of the feet. Lengthy experiments have proven that a foot housed in a shoe constructed in line with the present invention has normal blood circulation. Wearers of such shoes have been able to withstand very substantially greater strains in usage of the feet than when wearing shoes of conventional design and construction.

An object of the present invention is to provide a method of balancing a foot within a shoe to reduce bone and muscle strain and to prevent the outward overturning of the shoe upper over the edge of the sole.

Another object is to provide a device adapted to support the rear portion of the fifth metatarsal and its associated bones in a modern shoe.

Another object is to provide means for correcting modern shoe construction to secure foot balance within the shoe.

Another object is to provide means for utilizing the natural single longitudinal arch of the foot.

Another object is to provide means for alleviating the unnatural position of the fifth metatarsal when disposed in shoes of modern construction.

Another object is to provide means adapted to be used in a shoe to properly balance a foot to relieve muscle and bone strain and to prevent overturning of the upper over the sole.

Other objects and advantages will be apparent from the following description, taken in conjunction with the accompanying drawing, in which

Fig. 1 is an insert constructed in line with the present invention which is adapted to be disposed within a shoe to effect the purpose and objects of the present invention.

Fig. 2 is a section on the line 2—2 of Fig. 1.

Fig. 3 is a section on the line 3—3 of Fig. 1.

Fig. 4 is a central longitudinal section through a shoe showing an insert of the configuration of Fig. 1 disposed between the insole and the lining.

Fig. 5 is a section on the line 5—5 of Fig. 4.

Fig. 6 is a section on the line 6—6 of Fig. 5.

Fig. 7 is a transverse section through a last and associated shoe elements showing a modified means of effecting the present invention.

Fig. 8 is a diagrammatic view showing the bone structure of the outer side of the longitudinal arch disclosing the position of the fifth metatarsal relative to the os calcis when the latter is raised.

Fig. 9 is a diagrammatic view of the weight distribution through the bones of the foot.

Referring more particularly to the drawing by reference numerals, 10 indicates generally an insert for a shoe constructed in the light of the present invention. As is shown in Fig. 1, the insert 10 is generally elongated and is adapted to be disposed in a shoe, as is disclosed clearly in Figs. 4, 5 and 6. In a preferred configuration, the insert 10 is bevelled from the rear edge 11 forwardly to approximately the line 12 to provide a gradual support for the muscles and tissue forwardly of the supporting point of the os calcis. It is further provided with a sharp bevel 13 along the side which is remote from the outside of the shoe, the bevel 13 gradually widening forwardly, as at 14, to provide a general slope for effectively shifting the weight of the foot from the fifth metatarsal to the forward portion of the first metatarsal, which is the second main supporting point of the longitudinal arch. The outward edge 15 of the insert 10 conforms to the outward lines of the shoe and is substantially perpendicular, as can be seen from an inspection of Fig. 6. That portion of the upper side of the insert indicated 16 is substantially parallel to the under side, and is of a depth to properly support the fifth metatarsal and the associated bones. From the rear edge 4 of the portion 16 the insert slopes gradually rearwardly throughout the portion 5 to the line of intersection 12 with the bevelled portion 11. Likewise, from the front edge 6 of

the portion 16 the insert slopes gradually forwardly throughout the portion 7 to the line of intersection 8 with the bevelled portion 14. The base of the fifth metatarsal rests on the raised portion 16. It is to be understood, of course, that the insert 10 may be varied in certain of these details to conform to specific foot requirements.

In Figs. 4, 5 and 6 the insert 10 is shown in one disposition relative to the elements of a shoe. The illustrative shoe comprises an upper 18, a heel 19, an outsole 20, an insole 21, and a lining 22. The insert 10 is disposed between the lining 22 and the insole 21, though, of course, it could be inserted between the insole 21 and the outsole 20, if desired.

In Fig. 7 there is shown another means of effecting the present invention. A last 25 is constructed with a portion of the sole cut away at 26, that portion which is cut away being of a configuration substantially equivalent to the insert 10 shown in Fig. 1. The shoe is constructed on this preformed last in a manner to provide a built-up portion 27 between the outsole 28 and the insole 29. The built-up portion may be composed of strips of leather, composition, metal, or other material which will provide a firm built-up portion for the outer side of the longitudinal arch. The built-up portion 27 and the insert 10 are of a material firm enough to withstand the continual application thereto of the base of the fifth metatarsal; for, if it yields, the supporting effectiveness will be lost. However, it must be constructed and disposed so that the foot does not have the sensation of treading upon an obstruction within the shoe.

In Fig. 8 there is shown diagrammatically the disposition of the bones along the outer side of the foot when the foot is placed in a shoe having a heel. It will be observed that the os calcis 31 is a considerable distance above the forward portion 32 of the fifth metatarsal 33. The rear portion 34 of the fifth metatarsal assumes a position on a plane between those of the forward portion 32 and the os calcis 31. The relative positions of the phalanges 35, the cuboid 36 and the astragalus 37 are as shown. It is quite obvious that thus raising the os calcis 31 definitely forces the remaining bone structure to assume an unnatural position which the present invention positively corrects.

In Fig. 9, there is disclosed diagrammatically by the arrows 40 the line of body weight shifting in walking, which is from the position 41 of the os calcis to the position 42 of the forward position of the first metatarsal. This diagrammatic illustration emphasizes the forward rolling of the weight in walking along an arc of a circle. Clearly, if no support is afforded the base or rear portion of the fifth metatarsal, then the foot must roll outwardly to an extent which will deform the shoe and cause the upper to substantially overlap the edge of the sole. This undue rolling of the foot produces a continual strain on the muscles, the ligaments, and the bones of the foot which tires an individual in a very short time. Such rapid tiring of an individual palpably results in impaired and inefficient use of the pedal extremities and of the rest of the human mechanism; for tired feet result in a tired body and an irritated and restricted mental condition. Hence, to properly balance the feet will contribute materially to the total efficiency of an individual.

It is evident that there has been provided a method and means for balancing a foot within a shoe to eliminate and remove strain on the mus-

cles, ligaments, tissues, and bones of the foot. There has also been provided means for preventing undue rolling of the foot which habitually results in the overturning of the shoe upper over the edge of the sole which produces an unsightly appearance.

It is to be understood that the foregoing description and accompanying drawing have been given by way of illustration and example and not 10 for limitation, the invention being limited only by the following claims.

What I claim is:

1. A foot support for use in shoes and adapted to lie beneath the outer side of the longitudinal arch of the foot, including a first section elevated above the normal level of the inside of the shoe to support in elevated position the rear portion of the fifth metatarsal, said section being of substantially even height throughout its area, and 20 terminated at its rear short of the heel seat and at its front at a point shortly ahead of the said rear of the said fifth metatarsal, a second section extending forwardly from the said front portion of the first section and sloping downwardly 25 toward the inside level of the shoe, said second section extending forwardly under the front portion of the fifth metatarsal to provide positive support thereof at an elevation above the inside level of the shoe but at a less elevation relative

to the inside level of the shoe than is provided by the first section, said second section, ahead of the front of the fifth metatarsal, being then lowered to the inside level of the shoe.

2. A foot support for use in shoes and 5 adapted to lie beneath the outer side of the longitudinal arch of the foot, including a back section having a rear edge adapted to lie adjacent the os calcis and said back section extending forwardly from said rear edge and sloping upwardly from the normal level of the inside of the shoe to provide support for the portions forwardly and on the outer side of the os calcis, a middle section at the forward end of the rear section having a substantially constant elevation 15 above the inside level of the shoe, and extending beneath the rear of the fifth metatarsal to support such part above the normal level of the inside of the shoe, and a front section extending forwardly from the middle section, said front 20 section tapering downwardly from the middle section toward the front of the shoe, and extending beneath the front of the fifth metatarsal to support the same above the level of the inside of the shoe, said front section, ahead of the front 25 of the fifth metatarsal, being then lowered to the inside level of the shoe.

CHARLES P. LEYDECKER.
